UNITED STATES PATENT OFFICE.

ORRIL R. CHAPLIN, OF BOSTON, MASSACHUSETTS.

ROLLER-JOURNAL BEARING.

SPECIFICATION forming part of Letters Patent No. 400,053, dated March 26, 1889.

Application filed November 17, 1888. Serial No. 291,081. (No model.)

To all whom it may concern:

Be it known that I, ORRIL R. CHAPLIN, of Boston, in the county of Suffolk and State of Massachusetts, have invented certain new and useful Improvements in Roller-Journal Bearings, of which the following, taken in connection with the accompanying drawings, is a specification.

My invention relates to roller journal-bearings for shafts and axles; and it consists in certain novel features of construction, arrangement, and combination of parts, which will be readily understood by reference to the description of the drawings, and to the claims to be hereinafter given, and in which my invention is clearly pointed out.

Figure 1 of the drawings is a plan of an axle-bearing for street-cars embodying my invention. Fig. 2 is a vertical section on line $x x$ on Figs. 1 and 3. Fig. 3 is a horizontal section on line $y y$ on Fig. 2. Fig. 4 is an elevation of the inner end of the bushing or lining within which the bearing-rollers revolve. Fig. 5 is a longitudinal section of the same on line $z z$ and showing a small portion of the main casting in section and the means employed to prevent said bushing revolving within its casing in elevation. Fig. 6 is a transverse section of the roller-carrying frame with the rollers removed, the cutting plane being on line $w w$ on Fig. 7. Fig. 7 is a longitudinal section on line $v v$ on Fig. 6. Fig. 8 is an elevation of the end of the axle with the annularly-grooved thrust-collar secured thereon. Fig. 9 is a section on line $t t$ on Fig. 8, and Fig. 10 is an elevation of the forked ball-separator.

In the drawings, Λ is the main casing or shell of the bearing, having connected therewith by the ribs Λ' the spring supporting-seats Λ'' .

B is the axle provided with the shoulder a , and having secured to its end by the screws b the annularly-grooved collars c , provided in its outer face with an annular rabbet to receive the hardened-steel disk c' , as shown in Fig. 3.

The casing A is provided at one end with the inwardly-projecting flange d , and near the same end with the annular shoulder d' , against which one end of the bushing $e e'$

abuts, as shown. The bushing $e e'$ is divided obliquely into two parts, as shown in Figs. 4 and 5, so that the upper portion, e , which is subjected to the greatest wear, may be readily and easily removed and replaced by a new section whenever it becomes necessary. The lower section, e' , has formed in its inner end the slot e^2 with which the pin e^3 , set in the casing A and projecting inward therefrom, engages to prevent the bushing $e e'$ revolving in said casing, all as shown in Figs. 4 and 5. The axle B has fitted thereon in contact with the shoulder a the collar f , and between it and the collar c the sleeve g is so fitted to the axle as to revolve therewith, and upon this sleeve is mounted, so as to revolve thereon, a roller-carrying frame composed of the two heads or collars $h h$ and the tie-rods $h' h'$, secured in said heads, so as to maintain them at the proper distance apart. The openings through the heads or collars $h h$ are bushed with rings h^2 of suitable material, preferably of a fibrous nature—such as leatheroid or chemically-treated paper—which serves to reduce the friction of the surfaces, and thus render them more durable.

C are a series of bearing-rollers, each having a diameter equal to the distance between the exterior of the sleeve g and the interior of the bushing $e e'$ and a length nearly equal to the distance between the inner faces of the heads or collars $h h$, said rollers being arranged around the sleeve g at equal distances from each other, as shown in Fig. 2.

Between each two of the bearing-rollers C is a smaller roll, i , having its ends made frusto-conical and fitted to curved slots i' , formed in the heads or collars $h h$, the sides of which slots are inclined to fit the taper of the frusto-conical bearing ends of the rolls i , the length of the slots i' in the direction of the circumference of the head or collar being sufficient to permit a free movement to a limited extent of the rolls i about the sleeve g . The rolls i are of such a diameter as to fill the spaces between the rollers $C C$ and maintain them at a uniform distance apart, and their movement about the sleeve g is so limited by the ends of the slots i as to prevent the rollers $C C$ coming in contact with the tie-rods $h' h'$. (See Fig. 6.)

A ring, *j*, is fitted in the outer end of the casing *A* and abuts against the outer end of the bushing *e e'*, and against this ring bears the collar *k*, against which the ball *l*, resting 5 in the annular groove of the collar *c*, bears to take the endwise thrust of the axle or shaft in one direction, as shown in Fig. 3.

D is a cap chambered to inclose the collar *c*, which projects beyond the casing *A*, and 10 having formed therein a smaller chamber, in the bottom of which is fitted the disk *m*, in the inner face of which is formed a curved annular groove, in which roll the two balls *n*, which balls are kept at a uniform distance 15 apart by the fork-ended carrier *o*, pivoted to the center of the disk *m*, and bear against the disk *e'* to take the endwise thrust of the axle or shaft in the opposite direction. A disk of leather or other suitable material, *p*, 20 is secured to the inner end of the casing *A* by the annular cap or ring *E* and serves as a dust-guard.

The sleeve *g* may be dispensed with, if desired, and the rollers *C C* may bear directly 25 upon the axle; but I prefer to use the sleeve, because when it becomes badly worn it may be removed and replaced by a new one, and the axle remains as good as new.

It has been found necessary in practice to 30 have the outer casing or box of roller-bearings bushed, so that when the parts become badly worn said bushing may be removed and a new one inserted in its place, thereby avoiding the necessity of throwing away the main 35 casing or box; but heretofore said bushing has been made in one piece, which I have found to be quite objectionable for the reason that the constant rolling of the bearing-rolls within said bushing tends to expand it and pack 40 it so tightly into the outer casing as to render it difficult to remove it, and when removed the whole bushing had to be thrown into the scrap heap and an entire new bushing put in its place.

45 By making the bushing *e e'* in two parts divided obliquely, as shown and described, the upper portion, *e*, which is the only part subjected to any considerable wear, may be readily removed and a new section put in its 50 place without disturbing the lower section, *e'*.

The collars *c* and *k*, the disks *c'* and *m*, and the balls *l* and *n* are preferably made of steel and hardened.

What I claim as new, and desire to secure 55 by Letters Patent of the United States, is—

1. In a roller-bearing, the combination of an outer casing and a cylindrical bushing divided longitudinally into two parts, the plane of division being oblique to its axis.

2. In a roller-bearing, the combination of 60 an inclosing casing or box, a roller-carrying frame composed of two annular heads or collars connected together by a series of tie-rods, a series of bearing-rolls lying loosely between said heads or collars, a corresponding number 65 of smaller rolls having frusto-conical bearing ends and arranged one between each two of said bearing-rolls, each of said heads being provided with a corresponding number of curved slots having inclined sides to receive 70 the frusto-conical bearing ends of said smaller rolls.

3. In a roller-journal bearing, the combination, with the axle or journal, of the collars *c* and *f*, secured thereon, the roller-carrying 75 frame *h h h'*, fitted to said journal between said collars and revoluble thereon, the bearing-rollers *C C*, resting loosely between the heads of said revoluble frame without bearings therein, the smaller rolls, *i*, alternating 80 with said bearing-rolls and having bearings in said heads, and an outer casing or box inclosing the whole and having a cylindrical inner surface upon which the bearing-rollers travel as the journal or axle is revolved. 85

4. In combination with the axle or journal and the outer casing or box, the annular collar *k*, secured in a fixed position in the outer end of said casing, the collar *c*, secured to the end of said axle or journal and having formed 90 in its inner face an annular groove or pocket, a ball fitted in said groove or pocket and arranged to bear against the collar *k*, and to take the thrust of the shaft or axle in one direction, the cap *D*, inclosing said collar *c*, the 95 annularly-grooved disk *m*, fitted to a recess in said cap, the steel disk *c'*, set in the outer face of the collar *c*, and a ball or balls interposed between the disk *c'* and the annularly-grooved disk *m*, so as to take the thrust of 100 the shaft or axle in the opposite direction.

5. The combination of the casing or box, the axle or journal, the collars *c* and *k*, the cap *D*, the disk *m*, the balls *l* and *n*, and the ball-carrier *o*, all constructed, arranged, and 105 operating substantially as and for the purposes described.

In testimony whereof I have signed my name to this specification, in the presence of two subscribing witnesses, on this 1st day of November, A. D. 1888.

ORRIL R. CHAPLIN.
